UNITED STATES PATENT OFFICE.

GUY O. TANTLINGER, OF CHICAGO, ILLINOIS, ASSIGNOR TO HANS P. DANIELSEN, OF CHICAGO, ILLINOIS.

RECEPTACLE.

Application filed June 15, 1921. Serial No. 477,656.

To all whom it may concern:

Be it known that I, GUY O. TANTLINGER, a citizen of the United States, residing at Chicago, in the county of Cook and State 5 of Illinois, have invented a new and useful Improvement in Receptacles, of which the following is a specification.

My invention relates more particularly to receptacles such as hat boxes, trunks, hand 10 bags, suitcases and other receptacles, provided more particularly for wearing apparel, but not restricted thereto, of the character employing a strap or straps which are provided at the interior of the receptacle for strapping down the contents of the receptacle, more particularly when it is not completely filled, with a view to preventing objectionable shifting and disarrangement of the articles in the receptacle.

20 The common practice is to provide straps arranged at opposite sides within the receptacle, these straps being secured at their lower ends near the bottom of the receptacle and adapted to be connected together at their free ends, as by buckles, in a position 25 in which they overlap the contents of the receptacle. Such constructions, however, present the great disadvantage that the articles, particularly along the side walls of the receptacle from which the straps extend, are unduly mussed or wrinkled, the deeper the 30 body of articles introduced into the receptacle the greater the massing or wrinkling, due to the fact that the straps 35 extend from the bottom of the receptacle and in being drawn taut crowd the articles from opposite sides toward the center of the receptacle.

40 My primary object is to provide means in a receptacle whereby the contents thereof whether they fill the receptacle, or only partly fill it, may be held down in the desired position without crowding or forcing the contents at the sides of the receptacle 45 toward the center of the receptacle, and thus overcome the objections incident to receptacles as commonly provided and as hereinbefore explained.

50 Referring to the accompanying drawing: Figure 1 is a plan view of a suit-case provided with strap means constructed in accordance with my invention, the cover of the suit-case being shown as swung to open position. Figure 2 is a broken section taken 55 at the line 2 on Fig. 1 and viewed in the di-

rection of the arrow. Figure 3 is an enlarged, broken, view in sectional elevation taken through one of the strap devices of the preceding figures and illustrating the adjacent portion of the suit-case in sectional 60 elevation; and Figure 4, a view in front elevation, with certain parts broken away, of one of the guide devices employed.

In the particular construction illustrated, the body of the suit-case is represented at 5, it being provided along one edge with a cover 6 hinged thereto in accordance with common practice. My improved retaining means in the form shown comprise four straps represented at 7, 8, 9 and 10, these 70 straps being fixed at their lower ends to the body 5 of the suit-case, adjacent the bottom 11 thereof, and at opposite sides of the case, the straps 7 and 9 being shown as provided with buckles 12 and 13 respectively and the 75 adjacent free ends of the straps 8 and 10 apertured as indicated at 14 and 15 respectively to engage with the tongues of these buckles as shown in Fig. 1. The straps referred to extend, between their ends, through 80 loops 16 preferably of leather or similar material which extend adjacent the sides of the suit-case at which the straps referred to are secured, these loops engaging guides 85 along which they are movable up and down. The guides referred to and represented at 17 in the particular construction illustrated, are formed separately from the body 5 of the suit-case and preferably of leather strips with the ends thereof bent back upon themselves as represented at 18 and 19 at which 90 portions they are riveted as represented at 20 and 21, or otherwise secured, to the adjacent side walls of the body 5, to extend in spaced relation from said side walls as 95 shown in Figs. 2 and 3, these guides being preferably formed with relatively stiff strips 22, which may be of sheet-metal, preferably enclosed in the strap portions of the guides 17, as shown in Figs. 3 and 4. 100 The strap portions of the guides 17 are shown as each formed of a single length of strap folded upon itself crosswise thereof, with the edges of the folded-over portions stitched to the portions which they overlie 105 as represented at 23 to form a pocket in which the metal strips 22 are located, these metal strips being preferably secured at their lower ends to the strap portions of the guides 17, as by rivets, represented at 24, 110

which, in the particular construction shown, also serve as the means for securing the straps 7, 8, 9 and 10 at their lower ends to the receptacle.

5 The loops 16 being slidable up and down on the guides 17, and being in engagement with the straps 7, 8, 9 and 10 as stated, the elevation at which the free ends of the straps extend laterally toward the center of 10 the body 5 of the suit-case, may be varied as desired. Thus in Figs. 2 and 3 these loops 16 are shown as moved to a position on the guides 17 wherein they extend relatively close to the top of the body portion 5 which 15 represents one of the almost infinite number of positions which may be occupied by these loops in an upwardly-extending direction and which is the position these loops would occupy when the suit-case is only partly 20 filled with articles, the arrangement of the various parts being such, as shown, that the loops 16 will not slide down on the guides in the drawing of the straps to taut condition. It will be noted that the portions of the 25 straps which extend across the upper surface of the articles in the case, may be caused to extend substantially from opposite sides of the suit-case in substantially horizontal position, as distinguished from upwardly-con- 30 verging condition as would be the case should the loops 16 be omitted. The result is that there is no crowding of the articles engaged by the straps, in a direction from the sides of the suit-case toward the center 35 thereof which avoids mousing and wrinkling of the articles, and in accordance with the preferred construction shown the free ends of the retaining straps may be caused, by adjusting the loops 16 up or down, to extend 40 laterally from the sides of the body 5 at any desired elevation to suit varying conditions.

While I have illustrated and described the invention as applied to a suit-case, I do not wish to be understood as intending to limit it thereto as it has utility in connection with many other kinds of receptacles for receiving articles. Furthermore, I do not wish to be understood as intending to limit the invention to the particular construction of 50 device shown, as the same may be variously modified and altered without departing from the spirit of the invention.

What I claim as new, and desire to secure by Letters Patent is:

55 1. A receptacle having a retaining strap in its interior, guide means, and a loop mem-

ber through which said strap slidably extends, said loop member being adjustable up and down on said guide means adjacent a side of said receptacle and from which member said strap extends laterally toward the opposite side of the receptacle. 60

2. A receptacle having a retaining strap in its interior secured at its lower end to the 65 receptacle, a guide-member on said receptacle and located adjacent a side thereof, and a member slidable up and down on said guide, said member operatively engaging said strap between the ends of the latter and 70 slidable with respect to said strap and from which the free end of said strap extends laterally toward the opposite side of the receptacle. 75

3. A receptacle having a plurality of retaining straps in its interior at opposite sides thereof, spaced apart loop members at opposite sides of said receptacle and through which loop members said straps slidably extend, said members being movable up and 80 down adjacent the respective sides of said receptacle and from which the free ends of said straps extend laterally towards the opposite sides, respectively, of the receptacle, and means for connecting together the free 85 ends of said straps.

4. A receptacle having a plurality of retaining straps in its interior at opposite sides thereof, said straps being secured at their lower ends to the receptacle, spaced 90 apart members at opposite sides of said receptacle and adjustable up and down adjacent the sides thereof and with which said straps operatively engage, respectively, between the ends of the straps, the free ends of 95 said straps extending laterally from said members toward the opposite sides, respectively, of the receptacle, and means for connecting together the free ends of said straps. 100

5. A receptacle having a plurality of retaining straps in its interior at opposite sides thereof, said straps being secured at their lower ends to the receptacle, spaced apart members at opposite sides of said receptacle and adjustable up and down adjacent the 105 sides thereof and with which said straps slidably engage, respectively, between the ends of the straps, the free ends of said straps extending laterally from said members toward the opposite sides, respectively, 110 of the receptacle, and means for connecting together the free ends of said straps.

GUY O. TANTLINGER.
